UNITED STATES PATENT OFFICE.

STEDMAN P. CROUSE, OF BOSTON, MASSACHUSETTS.

CARD-HOLDER.

No. 806,525.

Specification of Letters Patent.

Patented Dec. 5, 1905.

Application filed June 20, 1905. Serial No. 266,121.

To all whom it may concern:

Be it known that I, STEDMAN P. CROUSE, a citizen of the United States, residing at Boston, in the county of Suffolk and State of Massachusetts, have invented certain new and useful Improvements in Card-Holders, of which the following is a specification, reference being had therein to the accompanying drawings.

My invention relates to certain improvements in card-holders adapted to be used for holding display-cards upon shelves and stacks of goods, and has for its principal object a holder adapted to be easily inserted between layers of goods piled in pyramid form and firmly held between said layers without inserting a prong or other sharp projection within the article itself or into the fabric of textile goods.

A full understanding of my invention can best be given by a detailed description of a preferred construction of my device which is inexpensive, simple, and durable, and a description of such a device will now be given in connection with the accompanying drawings, and the features forming this invention will then be specifically pointed out in the claims.

In the accompanying drawings, Figure 1 is a perspective view of one of the card-holders. Fig. 2 is a side elevation of the same card-holder, showing it inserted between two of the strips of a pyramid of goods. Fig. 3 is a front perspective view of the same card-holder. Fig. 4 is a side elevation of the card-holder so arranged as to hold two cards. Fig. 5 is a front elevation of one of my card-holders provided with coils for holding additional cards. Fig. 6 is a side elevation of the card-holder shown in Fig. 5.

Corresponding and like parts are referred to in the following description and indicated in all of the views of the drawings by the same reference characters.

My device is formed of a piece of wire having a central portion, two U-shaped loops on each side of the central portion, and a supporting portion at the outer end of each of the outside loops. The supporting portions 8 8' extend rearward from and at right angles to the upright portions 7 7', being flattened their entire length, and the greatest distance between them being at their extreme outer

ends and are adapted to be inserted between the layers a' a' of a stack of goods a. The right outer inverted-U-shaped loop is composed of the upright slanted portions 7 and 9, having its connecting portion 14 at a height nearly equal to the portion 12. The right inner U-shaped loop is composed of the upright slanted portions 9 and 10, so that it is readily seen that the portion 9 forms one side of both of the loops. The lower portion 15 of this inner loop is on the same plane as the portion 8 and forms part of the support, so that a very heavy metal card C could be inserted and held firmly in place. The left side of the wire forms two similar loops made by the slanted upright portions 7', 9', and 10', and the curved portions 14' and 15' are in the same planes, respectively, as the curved portions 14 and 15.

Each of the inner portions 10 10' is curved slightly rearward toward the portions 9 9' at or near their central portions 11 11', so as to form a securing means for a card c, inserted between the portions 9 10 and 9' 10', the connecting portion 12 being bent slightly forward, so as to allow of readily inserting a card. If desired, the portions 7' could also be curved slightly forward toward the portions 9' at or near their central part, as shown at 13 in Fig. 4, 8c so as to hold a downward-extending card c'. If desired, the portion 7' could also be bent into a double outward-extending coil 16 for holding a card c'', which coil would extend forward from the lower portion of the upper part 85 of the portion 7', but would not be forward of the portion 9, so that a card c could be held. A similar coil 16' for supporting a card c'' is formed on the upright portion 7', and the two flat horizontal portions 8 8' are 90 adapted to be inserted between goods b b'.

Having thus fully described my invention, what I claim as new, and desire to secure by Letters Patent, is—

1. A card-holder formed of a wire bent to 95 form two U-shaped loops on each side of its central portion, each outer loop being inverted and the outer ends of the wire flattened and extending horizontally rearward at right angles to the outer upright portions.

2. A card-holder formed of a wire having a central horizontal portion, two upright U-shaped loops on each side, each loop being bent to hold a card, and the ends of the wire

flattened and extending at right angles diagonally rearward.

3. A card-holder formed of a wire bent to form **U**-shaped loops on each side of its central portion, each outer loop being inverted and having its outer side formed into a double concentric coil, and each free end of the wire extending horizontally rearward at right an-

gles to the coil and flattened nearly its entire length, substantially as shown and described. 10

In testimony whereof I affix my signature in presence of two witnesses.

STEDMAN P. CROUSE.
